UNITED STATES PATENT OFFICE.

EDWARD F. McCOOL, OF VICTOR, COLORADO, ASSIGNOR TO THE McCOOL MFG. & TRADING CO., OF VICTOR, COLORADO, A CORPORATION OF COLORADO.

GEARING.

1,169,979.

Specification of Letters Patent.

Patented Feb. 1, 1916.

Original application filed September 13, 1911, Serial No. 649,209. Divided and this application filed April 4, 1914. Serial No. 829,668.

To all whom it may concern:

Be it known that I, EDWARD F. McCool, citizen of the United States, residing at Victor, county of Teller, and State of Colorado, have invented certain new and useful improvements in Gearing; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in grinding mills, special provision being made for pulverizing the material to be treated to an exceedingly fine mesh, if desired. In my improved construction, the grinding function is performed by two disks, to which the material to be ground is fed through a hopper carried by one of the disks which is non-rotary.

In my improved construction, I mount an operating shaft eccentrically within another shaft which will hereinafter be referred to as a hollow shaft, or sleeve. Power is transmitted initially to the hollow shaft upon which a fast pulley is mounted for the purpose. This hollow shaft carries a crank arm upon the outer extremity of which is mounted a gear which meshes with another gear fast on the operating shaft, whereby a rotary motion is transmitted to the operating shaft upon its own axis and at a faster speed than the rotation of the hollow shaft, the operating shaft being carried around in an orbit, so to speak, with the hollow shaft, during the rotary action of the latter. Hence the operating shaft has two movements, one on its own axis and the other a body or orbital travel with the hollow shaft, in which it is eccentrically mounted.

The invention covered by this application consists of the means for transmitting motion from one shaft to the other shaft, and is divided out of my previous application originally filed September 13, 1911, Serial No. 649,209, allowed June 17, 1913, renewed January 3, 1914, and again allowed January 8, 1914. Ser. 810,255.

Having briefly outlined my improved construction, I will proceed to describe the same in detail, reference being made to the

accompanying drawing, in which is illustrated an embodiment thereof.

In this drawing,—Figure 1 is a vertical longitudinal section taken through my improved grinding mill. This may be termed a section taken on the line 1—1, Fig. 2. Fig. 2 is a section taken on the line 2—2, Fig. 1, looking toward the right.

The same reference characters indicate the same parts in all the views.

Let the numeral 5 designate a suitable frame work in which is journaled a hollow shaft 6 within which is eccentrically mounted an operating shaft 7 whose forward extremity is fixedly connected with the block 8 to cause the said block to rotate with the shaft, the block having a dove-tail groove 9 adapted to receive a tongue 10 of counterpart shape formed on the grinding member 12, the grinding member being located on the said block by means of set bolts 13. The grinding member 12 extends into a hollow grinding head 14, including a grinding member 15 mounted on a plate 16, carrying a hopper 17, whose opening 18 registers with an opening 19 extending through the grinding member 15.

It must be understood that the specific construction of the grinding disks has nothing to do with my present invention. The only reason for the descriptions just given is to set forth one form of disk construction to which my improvement is applicable and as this form was illustrated in the parent application it is embodied in this divisional application.

The hollow shaft 6 is equipped with a fast pulley 47 secured thereto by bolts 48. It also carries a loose pulley 49. The opposite extremities of the hollow shaft are journaled in bearings 50 and 51 formed in the frame work of the machine, the said bearings having the usual Babbitt lining 52. These bearings are equipped with openings 53 for the introduction of lubricating material. The hollow shaft is also provided with perforations 54 and 55 through which the oil or other lubricant passes through the shell of the hollow shaft to the eccentrically mounted operating shaft 7. An anteriorly cogged ring 56 is mounted on the frame work, being secured in place by bolts 57 which pass through a flange 58 of the frame work, the ring 56 and a housing 59, the housing being further connected with a

sleeve 60 by means of bolts 61 passed through lugs 62 formed on the sleeve and threaded into the housing 59.

Within the sleeve 60 is movably located 5 a plug or block 63 whose forward extremity bears against the adjacent extremity of the operating shaft 7. The rear extremity of this block is engaged by a feed screw 64 which is threaded in the outer extremity 65 10 of the sleeve. As the feed screw is rotated in the proper direction, it acts upon the block 63 to move the operating shaft longitudinally and cause the rotary grinding member 12 to approach the relatively stationary grinding member 15.

The rear extremity of the hollow shaft 6 is equipped with a crank arm 66 carrying at its outer extremity a gear 67 which meshes with the interior cogs of the ring 20 56. This gear 67 also meshes with a gear 68 splined on the rear extremity of the operating shaft 7 as shown at 69. The relative size of the gears 67 and 68 is such that the 25 rotary action of the shaft 7 is considerably greater than that of the hollow shaft 6. This relation of course may be regulated as desired by changing the relative size of the two gears. By reference to Fig. 2 of the drawing, it will be understood that as the 30 hollow shaft 6 rotates in the direction of the arrow adjacent said shaft, the center of the gear 67 will be carried in an orbit, struck from the center of the hollow shaft with a radius equal to the distance of the 35 center of the hollow shaft from the center of the gear 67. While the axis of the gear 67 is traveling in this orbit, the gear itself will be rotated several times, since the number of cogs in the interiorly cogged gear 56 40 is several times the number of the gear 67, hence if the gears 68 were of the same size as the gear 67, the shaft 7 would be rotated several times during a single rotation of the hollow shaft or sleeve 6; and while as disclosed in Fig. 2 of the drawing, the gear 68 45 is slightly larger than the gear 67, the shaft 7 will be caused to make two and a fraction revolutions, while the shaft 6 is making a single revolution. It will be understood that 50 while the shaft or sleeve 6 is making a single revolution, its crank arm 66 causes the gear 67 to make a complete revolution in an orbit, the orbital travel being in the direction of the arrow adjacent the shaft or sleeve 6, while the travel of the gear 67 on its own axis is in the direction of the arrow adjacent the last named gear. From this 55 it will be understood that the relative speed of the two shafts 6 and 7 may be varied at will, by simply varying the relative sizes of the two gears 67 and 68. By virtue of this construction, it will be understood that power is transmitted to the hollow shaft

from a line shaft or motor (not shown), which is connected with the fast pulley 47, 65 and the rotary motion will be transmitted to the operating shaft 7, eccentrically mounted within the hollow shaft, as heretofore explained, the relative speed of the two shafts varying. The rotary motion of the operating shaft on its own axis is also transmitted to the grinding member 12, as well as the movement resulting from the orbital travel of the operating shaft with the hollow shaft, due to the fact that the axis of the operating 70 shaft does not coincide with the axis of the hollow shaft. Hence the grinding member 12 not only has a rotary movement due to the rotation of the operating shaft, but also a circular travel with the operating shaft 75 due to the eccentric mounting of the latter within the hollow shaft.

The fact that the two gears 67 and 68 will maintain their meshing relation during the orbital travel of the shaft 67, will be evident 80 when it is learned that the circle described by the center or axis of the gear 67 which is the center of the pin of the crank 66, is concentric with the circle described by the center or axis of the shaft 7 during its orbital 85 travel in and with the shaft 6. This being the case, the gears 67 and 68 will also maintain their meshing relation during the entire revolution or orbital travel of the gear 67, since the centers or axes of the two gears 90 are uniformly spaced throughout the said 95 revolutions or orbital travel of the gear 67.

Having thus described my invention, what I claim is,—

1. In a grinding mill, the combination 100 with a hollow shaft, an operating shaft eccentrically mounted therein and means for transmitting rotary motion from one shaft to the other shaft on its own axis, comprising a crank arm fast on one shaft and carrying a gear, a surrounding interiorly cogged gear with which the first named gear meshes, and a third gear fast on the operating shaft and with which the gear carried by the crank arm also meshes.

2. The combination of a hollow shaft, an operating shaft eccentrically mounted therein and extending longitudinally thereof, the hollow shaft being mounted to rotate and having a crank arm, a gear journaled on the 105 crank arm, an interiorly cogged stationary gear with which the gear carried by the crank arm meshes, and a third gear fast on the operating shaft and with which the crank arm gear also meshes.

In testimony whereof I affix my signature in presence of two witnesses.

EDWARD F. McCOOL.
